CLAIM

The ornamental design for a tank for use with portable apparatus for excrement disposal, as shown.

DESCRIPTION

FIG. 1 is a perspective view of a tank for use with portable apparatus for excrement disposal showing one embodiment of my new design;

FIG. 2 is a front view thereof;

FIG. 3 is a back view thereof;

FIG. 4 is a top view thereof;

FIG. 5 is a bottom view thereof;

FIG. 6 is a left side elevational view thereof; and,

FIG. 7 is a right side elevational view thereof.

The broken line showing is included for the purpose of illustrating and forms no part of the claimed design.
